UNITED STATES PATENT OFFICE.

DAVID F. VAUGHAN, OF HADDONFIELD, NEW JERSEY.

TIE-PLATE.

No. 823,826.

Specification of Letters Patent.

Patented June 19, 1906.

Application filed December 9, 1905. Serial No. 291,028.

To all whom it may concern:

Be it known that I, DAVID F. VAUGHAN, a citizen of the United States, residing at Haddonfield, Camden county, in the State of New Jersey, have invented certain new and useful Improvements in Tie-Plates, of which the following is a full, clear, and exact description, reference being had to the accompanying drawings.

10 The object of this invention is to provide a tie-plate of simple and efficient construction and adapted for use at either the meeting ends of two rail-sections in connection with a splice-bar or at points between the ends of a 15 rail-section.

As generally stated, the invention consists in providing the tie-plate with a longitudinal rib and spike-holes and arranging the spike-holes with relation to the rib to permit spikes 20 to enter said holes adjacent to the edge of the foot-flange of a rail when the rib is in engagement with the outer edge of the foot of a splice-bar or when the rib is in engagement with the outer edge of the foot-flange or a rail, 25 it being understood that the foot of the splice-bar extends outwardly beyond the outer edge of the foot-flange of the rail.

The invention consists, further, in providing the tie-plate with a depression arranged 30 with relation to the spike-holes and ribs to prevent a portion of the tie-plate from resting upon the tie or sleeper when said plate is used at points away from a splice-bar and the rib is in engagement with the foot-flange of 35 the rail, whereby the bearing-surface of the plate resting upon the tie on the inner or gage side of the rail will be no greater than the bearing-surface of the plate resting upon the tie on the outside of the rail, thus preventing the outward tilting of the rail due to 40 the outward pressure of a flanged wheel passing over the rail.

In the drawings, Figure 1 is a perspective view of a tie-plate embodying my invention. 45 Fig. 2 is an elevation of this tie-plate and adjuncts as used in connection with a rail at a point away from the splice-bars uniting two rail-sections. Fig. 3 is an elevation of this tie-plate and adjuncts as used in connection 50 with a splice-bar. Fig. 4 is a perspective view showing the tie-plate provided with an additional rib. Fig. 5 is an elevation of the tie-plate shown in Fig. 4 and adjuncts as used in connection with a rail at a point away 55 from the splice-bars. Fig. 6 is an elevation

of the tie-plate shown in Fig. 4 and adjuncts as used in connection with a splice-bar.

1 designates the body portion of the tie-plate, which is adapted to rest upon a tie or sleeper. Projecting from the upper face of 60 the plate 1 and to one side of the center thereof is a longitudinally-extending rib 2, the inner vertical wall of which is adapted to engage the outer edge of a splice-bar or the foot-flange of a rail, as will be hereinafter 65 explained. Formed in the lower face of the plate 1 and to the other side of the center thereof is a longitudinal depression 3, arranged substantially parallel to the rib 2, for a purpose hereinafter appearing.

The plate 1 is provided with two pairs of spike-holes 4 and 5, one pair of holes, 4, being adapted to receive spikes when the plate is used in connection with splice-bars and the other pair of holes, 5, being adapted to receive spikes when the plate is used in connection 70 with the rail at points away from the splice-bars. The distance between the two holes 4 of one pair at right angles to the rib 2 is substantially equal to the width of the foot-flange of a rail and to the distance between the two holes 5 of the other pair at right angles to the rib 2. One hole of the pair of holes 4 is arranged inwardly of the inner face of the rib 2, and the other hole of the pair of holes 4 is arranged outwardly of the inner edge of the depression 3, and one hole of the pair of holes 5 is arranged outwardly of the inner face of the rib 2, and the other hole of the pair of holes 5 is arranged inwardly of the inner edge of the depression 3, whereby when the inner face of the rib 2 is in engagement with the outer edge of a splice-bar spikes may enter the pair of holes 4 adjacent to the edges of the foot-flange of a rail, and when the inner face of the rib 2 is in engagement with the foot-flange of a rail spikes may enter the pair of holes 5 adjacent to the edges of said flange.

In Figs. 4, 5, and 6 I have shown a tie-plate of the same construction as that shown in Figs. 1, 2, and 3, excepting that the plate 1 is provided with an additional rib 6, projecting from the lower face of the plate parallel to the rib 2 and having its inner face in vertical alinement with the inner face of the rib 2, for a purpose hereinafter appearing.

When the tie-plate shown in Figs. 1, 2, and 3 is used at a joint between two rail-sections or in connection with a splice-bar 7, (see Fig. 3,) the face of the plate 1 provided with the

depression 3 rests upon the tie 8, the inner vertical wall of the rib 2 is in engagement with the outer edge of the splice-bar 7 on the outside of the rail as distinguished from the 5 inner or gage side thereof, and the holes are in position to permit the spikes 9 to be driven into the tie 8 adjacent to the edges of the foot-flange of the rail 10. In this position of the plate 1 it will be observed that its lower face 10 bearing upon the tie 8 extends outwardly beyond the outside edge of the foot-flange of the rail 10 a greater distance than it extends inwardly from the edge of the gage side of said flange.

15 When the tie-plate shown in Figs. 1, 2, and 3 is used in connection with the rail at a point away from a splice-bar, (see Fig. 2,) the face of the plate 1 provided with the depression 3 rests upon the tie 8, the inner vertical wall of 20 the rib 2 is in engagement with the outside edge of the foot-flange of the rail 10, and the holes 5 are in position to permit the spikes 9 to be driven into the tie 8 adjacent to the edges of the foot-flange of the rail 10. In 25 this position of the plate 1 its lower face, bearing upon the tie 8, extends outwardly beyond the outside edge of said flange as far as it extends inwardly beyond the inside edge thereof.

30 When the tie-plate 1 (shown in Figs. 4, 5, and 6) is used in connection with a splice-bar 7, (see Fig. 6,) the face of the plate provided with the rib 2 rests upon the tie, the rib 2 sinking into the tie, the inner vertical wall of 35 the rib 6 is in engagement with the outer edge of the splice-bar 7 on the outside of the rail, and the holes 4 are in position to permit the spikes 9 to be driven into the tie 8 adjacent to the edges of the foot-flange of the rail 10. 40 In this position of the plate 1 its lower face bearing upon the tie 8 extends outwardly beyond the outside edge of the foot-flange of the rail 10 a greater distance than it extends inwardly from the edge of the gage side of 45 said flange.

When the tie-plate shown in Figs. 4, 5, and 6 is used in connection with the rail 10 at a point away from the splice-bar, (see Fig. 5,) the face of the plate 1 provided with the depression 3 rests upon the tie 8, the rib 6 sinking into the tie, the inner vertical wall of the rib 2 is engagement with the outside edge of the foot-flange of the rail 10, and the holes 5 are in position to permit the spikes 9 to be 50 driven into the tie 8 adjacent to the edges of the foot-flange of the rail 10. In this position of the plate 1 its lower face, bearing upon the tie 8 extends outwardly beyond the outside edge of said flange as far as it extends inwardly beyond the inside edge thereof.

The advantage of the construction shown in Figs. 4, 5, and 6 is that when the tie-plate is used in connection with a splice-bar a greater area of bearing-surface for the plate 65 upon the tie is provided.

I claim—

1. A tie-plate having a longitudinal rib projecting from one of its faces away from the center thereof, said plate having a spike-hole arranged outwardly from the inner face 70 of said rib, and said plate having a spike-hole arranged inwardly from the inner face of said rib, the distance apart of the planes of the inner walls of said holes being substantially equal to the distance between the side of the 75 foot-flange of a rail and the side of the foot-flange of a splice-bar, substantially as and for the purpose set forth.

2. A tie-plate having a longitudinal rib projecting from one of its faces away from 80 the center thereof, and having two pairs of spike-holes, the distance between the two holes of one pair at right angles to said rib being substantially equal to the distance between the two holes of the other pair at right 85 angles to said rib, one spike-hole of one pair being arranged outwardly of the inner face of said rib, and one spike-hole of the other pair being arranged inwardly of the inner face of said rib, substantially as and for the 90 purpose set forth.

3. A tie-plate having a longitudinal rib projecting from one of its faces away from the center thereof, and a longitudinal rib projecting from the other of its faces, the inner 95 faces of said ribs being substantially in vertical alinement, said plate having a spike-hole arranged outwardly of the inner faces of said ribs, and said plate having a spike-hole arranged inwardly of the inner faces of said 100 ribs, the distance apart of the planes of the inner walls of said holes being substantially equal to the distance between the side of the foot-flange of a rail and the side of the foot-flange of a splice-bar, substantially as and 105 for the purpose set forth.

4. A tie-plate having a longitudinal rib projecting from one of its faces away from the center thereof, and a longitudinal rib projecting from the other of its faces, the inner 110 faces of said ribs being substantially in opposite alinement, said plate having two pairs of spike-holes, the distance between the two holes of one pair at right angles to said ribs being substantially equal to the distance between the two holes of the other pair at right 115 angles to said ribs, one spike-hole of one pair being arranged outwardly of the inner faces of said ribs, and one spike-hole of the other pair being arranged inwardly of the inner faces of said ribs, substantially as and for the 120 purpose set forth.

5. A tie-plate having a longitudinal rib projecting from one of its faces and arranged on one side of the center thereof, said plate 125 having a longitudinal depression in the other of its faces and arranged on the other side of the center of the plate substantially parallel to the rib, substantially as and for the purpose set forth.

6. A tie-plate having a longitudinal rib projecting from one of its faces and arranged on one side of the center thereof, said plate having a longitudinal depression in the other 5 of its faces and arranged on the other side of the center of the plate substantially parallel to the rib, said plate being provided with a spike-hole arranged outwardly of the inner edge of said rib, and said plate being provided with a spike-hole arranged inwardly of the inner edge of said rib, substantially as and for the purpose set forth.
7. A tie-plate having a longitudinal rib projecting from one of its faces and arranged 15 on one side of the center thereof, said plate having a longitudinal depression in the other of its faces and arranged on the other side of the center of the plate substantially parallel to the rib, said plate being provided with a spike-hole arranged outwardly of the inner edge of said depression, and said plate being provided with a spike-hole arranged inwardly of the inner edge of said depression, substantially as and for the purpose set forth.
- 25 8. A tie-plate having a longitudinal rib projecting from one of its faces and to one side of its center, said plate having a longitudinal depression formed in its other face and to the other side of its center and substantially parallel to said rib, said plate being

provided with spike-holes arranged outwardly of the inner edges of said rib and depression respectively, and said plate being provided with spike-holes arranged inwardly of the inner edges of said rib and depression respectively, substantially as and for the purpose set forth. 35

9. A tie-plate having a longitudinal rib projecting from one of its faces and to one side of its center, and a longitudinal rib projecting from the other of its faces, the inner faces of said ribs being substantially in opposite alignment said plate having a longitudinal depression formed in its other face and to the other side of its center and substantially 40 parallel to said ribs, said plate being provided with spike-holes arranged outwardly of the inner edges of said ribs and depression respectively, and said plate being provided with spike-holes arranged inwardly of the 45 inner faces of said ribs and depression respectively, substantially as and for the purpose set forth.

In testimony whereof I have hereunto affixed my signature.
